(57) **CLAIM**

The ornamental design for barbecue tool, as shown and described.

DESCRIPTION

FIG. 1 is the perspective view of a barbecue tool showing my new design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof; and,

FIG. 7 is the bottom plan view thereof.

The crosshatching, which is partially shown for ease of illustration, represents a conventional material and is understood to continue throughout the surfaces indicated.

1 Claim, 4 Drawing Sheets

FIG. 1

FIG. 3

FIG. 2
